(57) **CLAIM**

The ornamental design for a wheel chair dual hook support mechanism and rack, as shown and described.

DESCRIPTION

FIG. 1 shows a one-quarter right side perspective view of the presently disclosed wheel chair dual hook support mechanism and rack ornamental design;

FIG. 2 shows a left side one-quarter perspective isometric view of the presently disclosed wheel chair dual hook support mechanism and rack ornamental design;

FIG. 3 shows a left side orthographic view of the presently disclosed wheel chair dual hook support mechanism and rack ornamental design;

FIG. 4 depicts a right side orthographic view of the disclosed wheel chair dual hook support mechanism and rack ornamental design;

FIG. 5 depicts a front side orthographic view of the disclosed wheel chair dual hook support mechanism and rack ornamental design;

FIG. 6 provides a back side orthographic view of the disclosed wheel chair dual hook support mechanism and rack ornamental design;

FIG. 7 provides a top down orthographic view of a portion of the presently disclosed side orthographic view of the disclosed wheel chair dual hook support mechanism and rack ornamental design; and,

FIG. 8 provides a bottom up orthographic view of a portion of the presently disclosed side orthographic view of the disclosed wheel chair dual hook support mechanism and rack ornamental design.

The features of the wheel chair dual hook support mechanism and rack shown in phantom lines are not elements of the design of my new invention.
